OIL CLARIFIER

Donald H. Miller, Dayton, Ohio

Application March 24, 1933, Serial No. 662,424

5 Claims. (Cl. 210—131)

This invention relates to oil clarifiers and is particularly adapted for use in clarifying the oil circulated as a lubricant in the type of internal combustion engine employed for automotive purposes.

The conventional method followed in automotive practice comprises filtering, or, more properly, straining the oil, each time it is circulated through the lubricating system of the engine, 10 through a fine mesh screen, or through a piece of fibrous woven fabric, or a combination of both screen and fabric or felt.

As is well known these filters of common practice do not remove carbon particles or other fine 15 destructive dirt from the oil, with the result that each time it is circulated through the lubricating system it collects and retains additional foreign matter so that in a comparatively short time it is unfit for further use.

20 It is therefore the object of this invention to provide an oil clarifier different and superior to the filters and screens now commercially available, said clarifier comprising a special appliance which introduces the used and dirt laden oil into the presence of a highly adsorptive material having a particular affinity for the foreign matter which is known to be normally in commercial engine oils, or which is collected during its circulation through the lubricating system of 25 the conventional automotive engine.

I attain the foregoing object in the manner and with the means hereinafter described, reference being had to the drawings wherein—

Fig. 1 is a vertical section through the device 35 which I employ to put my invention into practice.

Fig. 2 is a schematic illustration of the application of my device to an internal combustion automotive engine.

40 Similar numerals refer to similar parts throughout the several views.

Referring now to Fig. 1, an outer casing generally designated by the numeral 8 comprises an outer cylinder 10 which has a bottom 12 crimped 45 pressure tight to the cylinder at its outer edge 14. The bottom 12 has an upwardly formed ledge 16 extending around its periphery at the inside of the cylinder 10.

The upper edge of the cylinder 10 has threads 50 20 pressed around its outer circumference. The extreme upper edge is formed inwardly to provide a flat rim 22 upon which a gasket 24 may rest. A lid 26 has pressed threads corresponding to the threads 20 of the cylinder 10. These 55 threads are preferably multiple rather than

single in order that the lid may be more quickly applied or removed. The lid 26 may preferably be knurled at its outer edge 28 whereby it may be more firmly grasped when it is put on or removed.

In the center of the bottom 12 a fitting 30 is secured and a flanged metal tube 32 is held to the end of the fitting by the hexagon nut 34. A similar fitting 36 is secured in an off center position of the bottom 12 and a second metal tube 10 38 is held to the end of the fitting 36 by the nut 40.

The cartridge generally designated by the numeral 41 contains the adsorptive material through which the used oil is made to percolate in its 15 process of filtration.

Cartridge comprises a cylindrical shell 42 having a bottom closure 44 crimped to the shell at the outer rim at 46. The closure 44 has a plurality of perforations 48. The upper end of 20 the cartridge has a top closure 50 which is crimped in the same manner at the outer rim at 52. The top closure 50 is not perforated.

A tube 54 extends through the center of the bottom closure 44 and passes upwardly to near 25 the top closure 50. The tube 54 is flanged at the end 56 to provide a more rigid connection to the closure to which it may be soldered or welded or otherwise secured. The lower end of the tube 54 is internally threaded at 58.

The fitting 30 is shouldered at 60 and immediately above the shoulder it is externally threaded to correspond to the threads 58 of the tube 54. A pilot portion 62 extends upwardly and is fitted freely into the inside of the tube 54. 35 When a cartridge 41 is placed in the casing 8 the pilot 62 guides the tube 54 so that the threads 58 of the tube will readily start over the corresponding threads of the fitting 30. Wings 63 are soldered or otherwise secured to 40 the top closure 50 to facilitate screwing the cartridge 41 in place. The wings 63 also provide means whereby the cartridge may be grasped in removing it.

The cartridge 41 contains the adsorptive material through which the used oil is filtered. In the present embodiment of the invention it is contemplated that the cartridge be filled and that the closures then be permanently attached, and when renewal of the contents is required an 50 new filled cartridge is supplied.

It has been found that a suitable adsorptive material for the device may comprise any of the vegetable, animal or mineral carbons, in powdered or granular form, preferably activated 55

to increase its adsorptive capacity. Either of these materials are highly porous and therefore present an almost incalculable total adsorbing surface to the oil as it passes therethrough.

- 5 In filling the cartridge with either of these materials a layer of fabric 64 is first laid in the bottom of the cartridge, then a layer 65 of waste, which may be cotton or other fibrous material. Adsorptive material 66 is then filled in to within 10 a short distance of the top. A second layer 68 of the same fibrous material as was placed near the bottom is now covered over the top, and the top closure 50 is fastened in place. The layer 64 of fabric effectively prevents any of the granular or powdered material from being lost by 15 passing out through the perforations 48.

By reference to Fig. 2 the general scheme of application and operation of the device will be evident. The engine 70 has the usual sump 72 20 and oil pump 74 driven by the shaft 76. The oil flows into the pump at 78 and out at 80 and through the pipe 82 to the parts to be lubricated. A second pipe 84 connects the outlet 80 to the central inlet of the clarifier 86 through 25 the pressure operated valve 88 and pipe 32.

When the pressure reaches a determined value in the pipe 82 any increase in the pressure causes the oil to flow through the valve 88 and pipe 32 upwardly through the tube 54 out at the top 30 of the tube and then through the waste bed 68, then downward through the adsorptive material 66, through the waste bed 65, then the fabric layer 64, out of the perforations 48, into the receiving space 90 and out through the pipe 38 35 back to the sump 72.

It will of course be understood that the circuit which the oil takes through the clarifier is arbitrarily selected, inasmuch as all of the oil may be made to pass through the clarifier before 40 any is pumped to the bearings.

Some of the advantages of the improved device may be stated as follows:

When oil enters the inlet 32 and passes upwardly through the central tube 54 of the clarifier 45 the waste bed 68 first mechanically strains out any coarse particles which may be present in the oil. The oil next percolates through the adsorptive material and in doing so comes in contact with the vast combined area of the inside of 50 the multitudinous pores. Inasmuch as these areas of the materials used have a particular affinity for free fatty acids occurring normally in lubricating oil and acids formed by the operation of the motor, these acids are removed 55 by being adsorbed to the surfaces of the pores. Other foreign matter, such as carbon, dirt and other solids which are fine enough to have passed

through the waste bed 68 are adsorbed to the pore areas in the same manner.

By consideration of the foregoing description it will be seen that the improved device herein disclosed not only strains out undesirable particles 5 of considerable size as do the filters now in commercial use, but it actually attracts and retains an infinite number of foreign particles so small that they pass with perfect freedom through any strainer that may be provided.

In this way the lubricating oil of the automotive engine is kept clean and fit for use for many times the length of time the same oil is now being used with ordinary so called filters.

Having described an embodiment of the invention wherein the objects set forth are attained,

I claim—

1. An oil clarifier comprising a vertically disposed cartridge having a perforated bottom end, 20 a layer of fibrous waste within said cartridge near each end, an adsorptive material filling the space between said fibrous layers, and a tube extending upwardly through the said perforated bottom to and into the upper layer of fibrous 25 waste.

2. The oil clarifier defined in claim 1 having a layer of fibrous fabric between the perforated bottom and the bottom layer of fibrous waste.

3. The structure defined in claim 1 having a 30 casing surrounding and enclosing said cartridge and means to hold the perforated bottom of said cartridge spaced apart from said casing.

4. The structure defined in claim 1 in which the lower end of the tube is internally threaded 35 and a casing surrounds and encloses said cartridge, and means holding the bottoms of said cartridge and casing spaced, comprising a pipe fitting extending into the bottom of said casing and upwardly into said casing and having a 40 shoulder, and a threaded portion above said shoulder screwed into the said internally threaded tube.

5. The combination with an engine, of bearing oiling mechanism comprising means containing 45 an oil sump, a pressure pump, means to convey oil from the sump to the pump inlet, means to convey oil under pressure from the pump outlet to the bearings, an oil filter, a pipe to convey oil under pressure from the pump outlet to the 50 filter, means to convey oil from the filter back to the sump, and a pressure operated valve in said pipe operable to be opened only to convey oil to said filter after the pressure on said bearings reaches a predetermined value. 55

DONALD H. MILLER.
